UNITED STATES PATENT OFFICE.

MILES VERNON, OF NEW YORK, N. Y.

COMBINATION DESK-PAD AND CLIP FOR HOLDING PAPERS.

No. 839,052.

Specification of Letters Patent.

Patented Dec. 18, 1906.

Application filed April 16, 1906. Serial No. 311,823.

To all whom it may concern:

Be it known that I, MILES VERNON, a citizen of the United States, residing at the borough of Brooklyn, in the county of Kings, city and State of New York, have invented a new and useful Improvement in a Combination Desk-Pad and Clip for Holding Papers, of which the following is a specification.

My invention relates to a pad and clip for holding loose sheets of paper for writing, with the object of providing an efficient, serviceable, and inexpensive device especially adapted for and within the reach of school children, students, &c.

My invention comprises a pad of binders' board or paper-board and a clip device at one end, beneath which loose sheets of paper are to be placed and held by force applied to the clip. The clip comprises a rectangular shaped piece of binders' or heavy paper board having two holes therein in a line parallel with the bearing edge of the board and the members of a double-twisted cord passed through the holes of the clip to and over the edges of the pad and across the back of the pad, the same being connected in any desired manner. The cords are twisted closely, and this causes the clip to bear with force upon the surface of the pad or upon any loose sheets of paper placed thereon beneath the edge of the clip. Increased tension may be applied by further twisting the cords.

In the drawings, Figure 1 is a plan view representing the improved device of my invention, and Fig. 2 is a vertical section on the dotted line $x-x$ of Fig. 1.

a represents the pad or writing-foundation of binders' or paper board. This may be left plain or may be surfaced with paper, as desired, and I prefer to form near one end and in the opposite edges notches a' .

b represents the clip, which is formed from a piece of binders' or heavy paper board of rectangular shape and provided with two holes $b' b'$, which are in a line parallel with the lower or bearing edge of the board, and c represents the members of a double-twisted cord. These cords, as will be seen from Fig. 1, pass in opposite directions over the opposite faces of the clip and through the holes b' and are twisted from the opposite edges of

the clip b to the edges of the pad a . These cords pass around over the edges of the clip and they are to be secured together against the back of the pad or board in any desired manner. These double-twisted cords pass around the edges of the board in the notches a' , and the twist is made close and strong. These notches serve the function of preventing the twisted cords moving out of place along the edges of the pad, and d represents loose sheets of paper, any number of which desired may be laid down upon the pad or board a and be placed under the lowermost edge of the clip b . The untwisting action of the twisted cords c forces the lower edge of the clip against the paper, exerting sufficient pressure to hold the sheets in position while they are being written upon, and should this clip not bear with sufficient force upon the paper additional tension may be given the same by turning the clip over and further twisting the cords.

This device is not only efficient and serviceable, but is exceedingly inexpensive, and it is especially adapted for and is within the reach of school children, students, &c.

I claim as my invention—

1. A desk-pad and clip for holding loose sheets of paper for writing, comprising a piece of binders' or similar board, a clip of binders' or similar board and twisted double cords connected to the clip and extending around the pad or binders' board near one end.

2. A desk-pad and clip for holding loose sheets of paper for writing, comprising a piece of binders' or similar board having opposite edge notches near one end, a clip of binders' or similar board of rectangular configuration having two holes therein in a line parallel with the bearing edge, and twisted double cords passing through the holes of the clip and around the edges of the pad in the notches thereof and said cords secured in position.

Signed by me this 11th day of April, 1906.

MILES VERNON.
